(57) **CLAIM**

The ornamental design for a basin for instrument reprocessor, as shown and described.

DESCRIPTION

FIG. 1 is a top perspective view of an embodiment of the basin for instrument reprocessor with a non-transparent lid covering the basin opening showing our new design;

FIG. 2 is a top perspective view of another embodiment of the basin for instrument reprocessor with a transparent lid covering the basin opening;

FIG. 3 is a top perspective view of the basin for instrument reprocessor depicted in FIG. 2 with the lid open;

FIG. 4 is a top perspective view of the basin for instrument reprocessor of FIG. 2 with the lid open; and,

FIG. 5 is a top plan view of the basin for instrument reprocessor of FIG. 2 with the lid open.

In the drawings, the broken lines depict unclaimed subject matter only and form no part of the claimed design.
